ASH TRAYS

Michael D. Vivolo, New York, N. Y.

Application August 12, 1953, Serial No. 373,713

5 Claims. (Cl. 220—20.5)

This invention relates to smokers' ash receivers, and has for one of its objects the provision of a device of this character which will receive and collect ashes from cigars and cigarettes in an efficient and sanitary manner.

It is another object of the invention to provide an ash receiver capable of one-handed operation and by means of which the top or closure member of the receiver can be opened and closed by one-fingered operation.

It is another object of the invention to provide a closure means for an ash receiver in the form of a pivotal plate which can be caused to swing to open or closed position by pressure imposed on a projection on top of the ash receiver.

It is a further object of the invention to provide an ash receiver of simple construction to effectively receive ashes; which can be easily cleansed of its accumulated contents and which will operate to confine the ashes and cigarette butts in a closed chamber.

With these objects, and other objects to be hereinafter set forth in view, I have devised the arrangement of parts to be described and more particularly pointed out in the claims appended hereto.

In the accompanying drawing, wherein an illustrative embodiment of the invention is disclosed,

Fig. 1 is a top plan view of an ash receiver constructed in accordance with the invention;

Fig. 2 is a front elevation of the ash receiver;

Fig. 3 is a view looking at the under side of the cover member of top of the ash receiver, showing the closure-plate operating mechanism;

Fig. 4 is a front view, with parts in section, of the closure-plate operating mechanism;

Fig. 5 is a view looking at the opposite side of the above mechanism;

Fig. 6 is an end view of the above mechanism;

Fig. 7 is a top plan view of another embodiment of the invention;

Fig. 8 is a view looking at the underside of the cover member, of the embodiment shown in Fig. 7;

Fig. 9 is a sectional view of portions of the cover member and closure plate, showing the pivot for the closure plate and the torsional spring surrounding the same; and

Fig. 10 is a sectional view through a portion of the cover member, showing the finger-piece and slot therefor.

Referring to the drawing and particularly to the embodiment of the invention shown in Figs. 1 to 6 inclusive, 1 indicated generally the body of the ash receiver. The same includes a bottom or tray portion 2, and a top or cover member 3. These parts are fitted together in any suitable manner, as by a telescopic fit; by threads or by bayonet joint, or in any other manner permitting them to be readily separated by manual operation, to enable the bottom or tray portion 2 to be emptied of the accumulated ashes and cigarette or cigar butts.

The top or cover member 3 is annular or of ring shape and is thus provided with the central opening 4, through which ashes, cigarette butts, etc., are deposited to fall into the bottom or tray portion 2 and be held thereby.

2

The central opening 4 of the cover member 3 is normally closed by means of a closure-plate 5, pivotally mounted on a pivot screw 6 extended into the under side of the cover member 3. This arrangement is such that by the eccentric pivotal mounting of the closure-plate, it can be swung to open position, or that shown in dotted lines in Fig. 1, by movement through the slot 7 provided in the side wall of the top or cover member 3. When in said open position, the central opening 4 will then be unimpeded and ashes dropped therethrough will fall into and be collected by the tray or bottom element 2 of the ash receiver.

The means for causing pivotal movement of the closure-plate 5 includes an angular bracket 8 which has a flange 9 attached to the under side of the top or cover member 3 by means of screws 10 or similar fastening elements. The bracket also includes a downwardly-extending or vertical flange 11 to which is pivoted, by the pivot pin 12, a triangulated rocking plate 13. At its lower end, the rocking plate 13 is provided with a pair of laterally-extending lugs indicated respectively at 14 and 15. Each of said lugs takes under a plunger pin constituting a push button, the pin which engages the lug 14 being shown at 16 while that engaging the lug 15 being shown at 17. These plunger pins are slidable through openings 18 formed in the top 3 of the receiver, and each of the pins is formed with a shoulder 19 to prevent it from falling out of the receiver when the same is held upside down.

At the upper end of the rocking plate 13 is provided a laterally-extending lug 20 which pivotally receives one end of a link 21, the opposite end of the link being in pivotal engagement with an ear 22 formed on the closure plate 5. This coupling between the rocking plate 13 and the closure plate 5 is such as to cause the closure plate to be moved to its closed position, shown in full lines in Figs. 1 and 2, when the rocking plate 13 is in one of its angular positions and to be swung outwardly through the slot 7 to its open position, shown in dotted line in Fig. 1, when the plate 13 is reversely pivoted. The rocking action of the plate 13 is attained by pressure imposed on one or the other of the plunger pins 16 and 17.

The closure plate 5 is held from inadvertent shift from either its closed or open position by means of a coil spring 23 having one end engaged with the lug 20 on the rocking plate 13 and its other end engaged with an ear 24 extending laterally from the flange 11 of the bracket 8. A stop 25 limits the swing of the closure plate 5 to its closed position by contact with a lug 26 provided at one edge of the closure plate.

From the foregoing, the operation of the improved ash receiver will be readily understood. The normal or closed position of the same is that shown in full lines in Fig. 1, wherein the central opening 4 in the top of the receiver is closed at the bottom by the closure plate 5, and at this time the push button or plunger pin 17 has its upper end projecting well above the top or cover member 3 for easy finger engagement. If ashes are deposited in the tray at this time, the same will fall on the closure plate 5 and be held thereby. Finger pressure imposed upon the elevated plunger pin 17 will depress said pin and cause the same to rock the plate 13 and cause the same, through its connection to the closure plate 5 by means of the link 21, to swing the closure plate 5 to its open position shown in dotted lines in Fig. 1.

As the closure plate 5 is pivotally swung to such open position, the ashes resting on its upper face will be wiped off the same by contact with the inner edge 27 of the top member surrounding the opening 4 and the ashes will fall down into and be captured by the tray or bottom member 2 of the receiver. When the plunger pin 17 is depressed as above described, and the closure plate 5 is thus swung to open position, the rocking movement of the plate 13

will cause elevation of the second plunger pin, or that shown at 16, so that when the closure plate 5 reaches its open position, the plunger pin 16 will be in an elevated position while that shown at 17 will be in lowered position. To move the plate to its closed position merely requires manual depression of the plunger pin 16 whereupon the rocking plate 13 will be swung in a direction to cause the closure plate 5 to be moved back to its closed position. It will be noted that the flange 11 of the bracket 8 is formed with a cut-out or aperture 28 in a manner to clear the lug 20 on the rocking plate.

While it has been suggested that ashes can be deposited in the receiver while the plate 5 is in its closed position, and said ashes caused to be dropped in the tray or bottom of the receiver by the swing of the plate, the device can be used with the plate 5 in open position, and the ashes dropped directly into the bottom or tray portion, after which the closure plate 5 is swung to closed position to cover and conceal the deposited ashes. Regardless of the manner in which the device is used, it will be apparent that it is capable of simple one-handed push-button operation. The device is cleaned of its contents by the easy removal of the bottom portion or tray of the receiver, and for convenience, the top or cover member 3 can be provided with depressions 30 or other suitable supports for cigars or cigarettes.

For the purpose of more readily disclosing the construction of the operating parts of the device, these parts are shown as exposed in the bottom or tray portion of the receiver. In actual practice, it is possible that these parts of the device shall be enclosed in a suitable housing to thereby keep the same free from contact with the ashes deposited into the tray or bottom of the receiver.

In the embodiment of the invention shown in Figs. 7 to 10 inclusive, the closure plate 5 is shown as mounted upon a pivot pin 40 on which the plate is swingable to open or closed positions. Surrounding the pivot pin 40 is a torsional spring 41 having a projecting end 42 anchored in the top or cover member 3 as shown at 43. The opposite end 44 of the spring 40 is engaged with the closure plate 5 in such a manner that the torsional effect of the spring tends to maintain the closure plate 5 in its closed position as shown in Fig. 8. Extending upwardly from the top of the closure plate 5 is a pin 45 terminating at the top in a knob 46 or other projection constituting a finger piece by means of which the plate may be swung to open position against the torsional effect of the spring 41. The pin 45 is movable through an arcuate slot 47 provided in the top or cover member 3 of the receiver.

In this embodiment of the invention, the closure plate is moved to open position by pressure of the finger against the knob 46 in a manner to move the pin 45 through the slot 47 and thus swing the plate 5 to open position, or that shown in Fig. 7. Upon release of pressure on the knob end of the pin 45, the spring 41 will cause the plate 5 to be swung to its closed position.

Having described two embodiments of the invention, it is obvious that the same is not to be restricted thereto, but

is broad enough to cover all structures coming within the scope of the annexed claims.

What I claim is:

1. An ash receiver having an ash-containing chamber and a centrally-apertured cover therefor, push-buttons operable through the cover, a rocking member pivotal below the cover and within the chamber and caused to rock by depression of one or the other of the push-buttons, a pivoted closure plate adapted to normally close the bottom or the central-aperture in the cover, and means coupled to the closure plate and to the rocking member by which pivotal movement of said closure plate to either open or closed position is attained by depression of one or the other of the push-buttons.
2. An ash receiver having an ash-containing chamber and a centrally-apertured cover therefor, push-buttons operable through the cover, a pivoted closure plate adapted to normally close the bottom of the aperture in the cover, and means coupled to the closure plate and to the push buttons by which pivotal movement of said closure plate to either open or closed position is attained by depression of one or the other of the push-buttons.
3. An ash receiver having a bottom, a centrally-apertured top fitting thereon, a pivotal plate carried by the top and normally closing the lower end of the aperture therethrough, a rocking member, a link extending between said member and the pivotal plate and causing swing of said plate to either open or closed position upon rocking movement of said member, and a pair of push buttons operable on said rocking member to rock the same to either of two positions.
4. An ash receiver having a bottom, a centrally-apertured top fitting thereon, a bracket secured to the under side of the top, a rocking plate pivoted on the bracket, a closure plate pivoted on the under side of the top, said plate in its closed position acting to close the lower end of the aperture in the top, a link extending between the closure plate and the rocking plate whereby swinging of the rocking plate will move the closure plate to either its open or closed position, and a pair of push-buttons in engagement with the rocking plate in a manner to cause one of the push buttons when depressed to swing the rocking plate in an opposite direction and pivotally move the closure plate to closed position.
5. An ash receiver as provided for in claim 4, wherein a spring extends between a portion of the rocking plate and the bracket, the push buttons extending vertically through openings in the top, one of the buttons being elevated when the other is depressed, and stop means for limiting the swing of the closure plate to its closed position.
